UNITED STATES PATENT OFFICE.

ABRAHAM L. KELLER, OF ELGIN, ILLINOIS, ASSIGNOR OF ONE-THIRD TO
OTTO JOHNSTON, OF SAME PLACE.

PENDANT-STEM FOR WATCHES.

SPECIFICATION forming part of Letters Patent No. 353,749, dated December 7, 1886.

Application filed February 23, 1886. Serial No. 192,960. (No model.)

To all whom it may concern:

Be it known that I, ABRAHAM L. KELLER, a citizen of the United States, residing at Elgin, in the county of Kane and State of Illinois, 5 have invented a new and useful Improvement in Crown-Stems for Stem-Winding and Hand-Setting Watches, of which the following is a specification.

My invention relates to improvements in 10 stem-winding and hand-setting mechanism for watches, in which the crown-stem is made in two sections; and it consists in having the section with the knob provided with a square hole in the end of its stem part, and a suitable 15 spring with a catch secured to said stem, and having its catch arranged to project into said square hole to engage the other section of the stem, in the manner hereinafter specified.

The objects of my improvements are, first, to 20 provide means whereby the works of the watch can be taken out of the case without taking it apart; second, a stem that can readily be adapted to the common pendant-setting watches, and to facilitate the removal of the works from 25 the case. I attain these objects by the mechanism illustrated in the accompanying drawings, in which—

Figure 1 is a longitudinal section of my improved mechanism, and Figs. 2 and 3 are 30 detail parts of the same.

Similar letters of reference refer to similar parts throughout the several drawings.

In the drawings, *k* is a section of the watch-case with the pendant *l* attached, into which is 35 fitted my improved crown-stem *a* and *b*. The section *a*, forming the crown-knob, is provided with a groove, *h*, into which enters the stop-screw *i*, and determines the endwise movement 40 of the crown-stem when the same is operated in winding up the watch or setting the hands, as the case may be. The end of this stem is provided with a square hole, and at its side is 45 provided with a spring, *e*, having a hook at its end, which projects at a short distance from the end of the stem into the square hole. (See Fig. 2.) The section *b* has its end to correspond with the square hole of section *a*, and is provided with a catch or notch, *f*, to engage the

hook on the end of the spring *e*, and thus hold the two sections *a* and *b* coupled. A collar, *g*, 50 near the other end of section *b* is provided, which operates in conjunction with a suitable lever, *d*, or its equivalent, whereby the setting and winding mechanism is manipulated. A bevel-pinion, *c*, is also provided, which fits upon 55 the square beyond the collar. This bevel-pinion gears with the gear of the winding and hand-setting mechanism.

When it is necessary to remove the watch or works from the case, the stop-screw *i* is screwed 60 back until the crown-stem is free from said screw. The stem can now be pulled out until the part *b* is drawn from the bevel-pinion *c*. The watch or works can now be removed from the case without taking it apart. The stem 65 part *b* can now readily be removed from the knob-section *a* by uncoupling it. This is done by lifting the spring-hook *e*. With this construction any style of stem-winding watch that will fit the case can be used by simply providing 70 a suitable stem-section, *b*. It obviates the use of the crown without a stem-winding movement in case a key-winding movement is desired for the same case, instead of a stem-winding movement.

Having now fully described my invention, 75 what I desire to secure by Letters Patent is—

1. In a pendant-winding and hand-setting watch, a crown-stem made in two sections, the crown or knob section provided with a spring-hook, *e*, and its pinion-section provided with a square and notch to couple with the crown-section, in the manner shown, for the purpose set forth.

2. In a pendant-winding and hand-setting 85 watch, a crown-stem made in two sections, the crown or knob section having a square hole in its end and a transverse kerf on its side, near its end, to admit of the spring-hook *e*.

3. In a pendant-winding and hand-setting 90 watch, a crown-stem made in two sections and having a spring provided with a hook for coupling the two sections together, in the manner and for the purpose set forth.

4. In a pendant-winding and hand-setting 95 watch, a crown-stem made in two sections, hav-

ing the crown or knob section provided with a groove, *h*, to determine the endwise movement of the stem, operating in conjunction with a set-screw in the ring-pendant.

5. The combination, substantially as hereinbefore set forth, of a crown-stem made in two sections, *a* and *b*, the spring *e*, set-screw *i*,

bevel-pinion *c*, and lever *d*, these members being constructed and arranged for the purpose specified.

A. L. KELLER.
